UNITED STATES PATENT OFFICE.

GILBERT TOLLEFSON, OF BAGLEY, MINNESOTA.

CONVEYING SYSTEM.

1,103,709.

Specification of Letters Patent. Patented July 14, 1914.

Application filed June 26, 1913. Serial No. 775,866.

To all whom it may concern:

Be it known that I, GILBERT TOLLEFSON, a citizen of the United States, residing at Bagley, in the county of Clearwater and 5 State of Minnesota, have invented certain new and useful Improvements in Conveying Systems; and I do hereby declare the following to be a full, clear, and exact description of the invention, such as will enable others 10 skilled in the art to which it appertains to make and use the same.

My invention has for its object to provide an improved conveying, sorting, screening, sacking, and distributing system especially 15 adapted for use in handling potatoes in warehouses and, to this end, it consists of the novel devices and combinations of devices hereinafter described and defined in the claims.

20 In the accompanying drawings, which illustrate the invention, like characters indicate like parts throughout the several views.

Referring to the drawings: Figure 1 is a view partly in side elevation and partly in 25 longitudinal vertical section, showing the receiving end of the improved system; some parts being broken away; Fig. 2 is an end elevation of the same; Fig. 3 is an end elevation of the delivery end of the improved 30 system with the distributing belt removed and some parts shown in vertical section, on an enlarged scale; Fig. 4 is a detail view in perspective, showing the delivery end of one of the sack filling spouts; Fig. 5 is a plan 35 view of the delivery end of the improved system with the sack filling spouts removed, some parts being broken away; and Fig. 6 is a side elevation of the parts shown in Fig. 5, some parts being broken away, and 40 some of the exposed parts being shown in vertical section.

The numerals 1 and 2 indicate, respectively, the first floor and the basement of a warehouse. Located substantially in the 45 same plane with the floor 1 is a scale platform 3. A horizontally extended conveyer trough 4 is suspended within the basement 2, by timbers 5, from the floor 1, at an elevation below the scale platform 3. An inclined 50 spout 6 is rigidly secured to the scale platform 3 and its delivery end is arranged to deliver into the conveyer trough 4. A conveyer 7, comprising a pair of laterally spaced link belts 8 connected by a plurality

of round iron slats 8^a, is mounted in the 55 trough 4, and the link belts 8 run over front and rear pairs of alined sprocket wheels 9 secured, respectively, to a power shaft 10 and an idle shaft 10^a journaled in the sides of the trough 4. The upper runs of the link 60 belts 8 are guided by rails 11 secured to the sides of the conveyer trough 4, and the lower run of said belts travel over and are supported by the deck or bottom of the conveyer trough 4, the purpose of which will 65 presently appear. A hopper or bucket 12, for receiving the refuse, is suspended by a bail 13 from the scale platform, directly under the receiving end of the conveyer trough 4. In one side of the hopper 12 is 70 mounted a gate 14 which slidably works between cleats 15 secured to said hopper. An operating rod 16 is secured to the gate 14 and projects above the floor 1. This rod affords means by which the gate may be 75 lifted, to dump the refuse from the hopper 12.

Potatoes, after being weighed on the scale 80 platform 3, are dumped down the inclined spout 6 onto the conveyer slats 8^a and hence carried by said conveyer to the delivery end 85 of the conveyer trough 4. Refuse, such as dirt and small potatoes, will be screened through the slats 8^a and deposited on the deck of the conveyer trough 4. The lower run of the conveyer 7 working over said deck, in the direction of the arrow marked on Fig. 1, will scrape all refuse deposited thereon into the hopper 12. The ends of the shaft 10 are extended outward of the conveyer trough 4 and journaled in bearings 17 mounted on the frame work 18 secured to certain of the timbers 5. Mounted on one end of the shaft 10 are fast and loose pulleys 19 and 20, respectively, over either one of 90 which runs a belt, not shown, for driving the conveyer 7.

At the delivery end of the conveyer 7 is located a pair of reversely extended sack filling spouts 21 arranged to deliver to either 100 side of the conveyer 7. To the delivery end of each spout 21 are secured front and rear sack holding cleats 22 and 23, respectively. The upper edges of the cleats 23 are inwardly and downwardly beveled, to assist in 105 holding sacks Z, the mouths of which are telescoped directly over the delivery ends of said spouts 21. Turn buttons 22^a are pro-

vided for clamping said sacks onto the cleats 22, thereby completing the sack holding means. Hinged at 24 to the junction of the bottoms of the two spouts 21 is a swinging 5 gate 25, adapted to be moved into positions to close either one of the two spouts 21. This gate 25 also acts as an extension of the bottom of the spouts 21 which are open and onto which the potatoes are delivered from 10 the conveyer 7. Reversely extended cables 26 are provided for operating the gate 25. To prevent bruising of the potatoes, the sides of the conveyer trough 4 and the spouts 21 are, preferably padded and lined with 15 any suitable material.

Located adjacent to one side and at the delivery end of the conveyer trough 4 is an elevator shaft 27 which extends from the floor of the basement 2 through the floor 1. 20 Mounted in the elevator shaft 27 is an elevator not shown, for elevating the sacks Z when filled from the spout 21.

Extending transversely of the delivery end of the conveyer trough 4, outward of 25 the sack filling spouts 21, is a horizontally extended distributing belt 71 mounted to run over a driven roller 72 and a loose roller 72^a. These rollers are journaled in laterally spaced side plates 73 which, together 30 with the belt 71, afford a trough. Potatoes are delivered from the conveyer 7 to the distributing belt 71 over an incline spout 74, pivotally secured to the shaft 10. To the trunnion of the roller 72 is keyed a bevel 35 gear 75 with which meshes either one of a pair of laterally spaced bevel gears 76 keyed to a shaft 77 which is journaled in bearings 78 on a suitable support 79. To one end of the shaft 77 is keyed a pulley 80 over 40 which runs a driving belt, not shown, and on the other end of the shaft 77 is keyed a shipper collar 81. A shipper lever, not shown, may be applied to this collar 81, for moving the gears 76 into and out of mesh 45 with the bevel gears 75. By these gears 76, the distributing belt 71 may be driven in either direction, at will.

Pairs of opposite gate openings 82 are formed by cutting out sections of the side 50 plates 73. These cut-out sections afford gates 83 which are hinged at 84 to the side plates 73. Opposite gates 83 are connected in pairs, for simultaneous movement, by links 85. Downwardly inclined discharge 55 spouts 86 are attached to the side plates 74 in positions to receive from the distributing belt 71 either at the ends thereof or through the front gate openings 82. By turning the gates 83 into alinement with the 60 side plates 73, the gate openings 82 are closed and the passageway between the said side plates is opened, permitting potatoes to be delivered by the distributing belt 71 to either of the end discharge spouts 86. 65 When the gates 83 are turned into positions

indicated by full lines in Fig. 10, the gate openings leading to the side spouts 86 are open and one of each pair of said gates extends obliquely across the passageway between the side plates 73, forming a continuation of one of the sides of the side spouts 86 and also affording a scraper to discharge the potatoes carried by the distributing belt 71 through the gate openings 82 leading to the side spouts 86. The free 70 ends of the discharge spouts 86 will, in actual practice, be arranged to deliver into various bins within the warehouse.

The operation of the improved system may be briefly stated as follows:

The potatoes hauled to the warehouse are first weighed on the scale platform 3 together with the vehicle, to secure the gross weight. The potatoes are then dumped onto the conveyer 7 and carried thereby to the 75 delivery end of said conveyer. All dirt, rubbish, and small potatoes will be screened through the conveyer 7 and deposited on the deck of the conveyer trough 4, from which they are scraped, by the lower section of 80 the conveyer 7, into the hopper 12. As the potatoes roll down the spout 6, all rotten and defective ones may be thrown into the hopper 12. After the load of potatoes is removed by the conveyer 7, the vehicle, together with the waste deposited in the hopper 12, is again weighed to find the tare which, subtracted from the gross weight, will give the net weight. At the delivery 90 end of the conveyer 7, the potatoes may be directed to the sacking spouts 21 by raising the spout 45 into an inoperative position, or they may be directed onto the sorting belt 71 by turning the spout 45 into the position indicated in Figs. 3 and 10. From the sorting belt 71, the potatoes may be delivered to any one of the several bins in the warehouse by simply changing the position of the gates 83 and the direction of travel of 95 said belt. After each load has been removed 100 by the conveyer 7, the waste in the hopper 12 may be dumped.

All the parts of the improved system are so located as to take up very little room in the warehouse and they are extremely easy 115 to operate, thus making the handling of the potatoes an easy matter. By the use of my improved system, the cost of handling potatoes in the warehouse is greatly reduced. Potatoes are also thoroughly screened while 120 they are carried on the conveyer 7, without being bruised or skinned. The disposition of each load is greatly expedited, thereby relieving the farmer from wasting time waiting his turn to unload. It also enables 125 the buyer to thoroughly examine each load of potatoes as the same roll down the chute 6 from the scale platform to the conveyer, at which time all rotten and defective potatoes may be removed. Thus he pays only 130

for the good potatoes. It is, of course, understood that this device may be used for handling all kinds of produce.

What I claim is:

- 5 1. In a device of the kind described, the combination with a conveyer arranged to receive commodities, of a distributing belt and a sack filling spout at the delivery end of said conveyer, and means for causing said 10 conveyer to deliver to either said distributing belt or said sack filling spout, substantially as described.
2. In a device of the kind described, the combination with a conveyer arranged to receive commodities, of a distributing belt extending transversely of the delivery end of said conveyer, means for driving said distributing belt in either direction, at will, a sack filling spout at the delivery end of said 15 20 conveyer, and means for causing said conveyer to deliver to either said distributing belt or said sack filling spout, substantially as described.
3. In a device of the kind described, the combination with a conveyer arranged to receive commodities, of a distributing belt extending transversely of said conveyer, means for driving said distributing belt in either direction, at will, reversely extended 25 30 sack filling spouts at the delivery end of said conveyer, and independent means for causing said conveyer to deliver, at will, to either of said sack filling spouts or to said distributing belt, substantially as described.
- 35 4. In a device of the kind described, the combination with a trough, of a slat and belt conveyer mounted in said trough with its lower portion arranged to travel over the bottom thereof and to scrape materials from 40 45 the said trough which have been screened through the upper portion of said conveyer, a distributing belt extending transversely of the delivery end of said conveyer, reversely extended sack filling spouts at the delivery end of said conveyer, a gate for closing either of said sack filling spouts, and means for causing said conveyer to deliver into either of said sack filling spouts or to said distributing belt, substantially as described.
- 50 5. In a device of the kind described, the combination with a trough, of a distributing belt mounted in said trough, a gate opening in one side of said trough, and a pair of gates hinged to the sides of said trough and connected, for simultaneous movement, said 55 gates being arranged, one to open and close said gate opening, and the other to open and close the passageway through said trough, the gate closing said passageway arranged to deflect material carried by said 60 belt through said gate opening, substantially as described.
6. In a device of the kind described, the combination with a trough, of a distributing belt mounted in said trough, a gate opening 65 in one side of said trough, a pair of gates hinged to the sides of said trough and connected, for simultaneous movement, said gates being arranged, one to open and close said gate opening, and the other to open 70 and close the passageway through said trough, the gate closing said passageway arranged to deflect material carried by said belt through said gate opening, means for driving said belt in either direction, at will, 75 and spouts arranged to receive material delivered from either end of said belt or through said gate, substantially as described.
7. In a device of the kind described, the combination with a trough, a distributing 80 belt mounted in said trough, means for driving said belt in either direction, at will, a pair of gate openings in the sides of said trough, pairs of gates reversely hinged to the sides of said trough, the gates of each 85 pair being connected, for simultaneous movement, said pairs of gates being arranged, one to open and close said gate openings, and the other to open and close the passageway through said trough, the gates closing 90 said passageway arranged to deflect material carried by said belt through said gate openings, and spouts arranged to receive material delivered from either end of said belt or through either of said gate openings. 95

In testimony whereof I affix my signature in presence of two witnesses.

GILBERT TOLLEFSON.
